United States Patent Office

Des. 187,622
Patented Apr. 5, 1960

187,622

CINE CAMERA

Yoshimasa Ushiyama, Tokyo, Japan, assignor to Yashima
Kogaku Kogyo Kabushiki Kaisha, Tokyo, Japan

Application January 7, 1958, Serial No. 49,161

Claims priority, application Japan July 13, 1957

Term of patent 14 years

(Cl. D61—1)

FIG. 1

FIG. 2

FIG. 3

FIG. 4

FIG. 5

FIG. 6

Fig. 1 is a top plan view of a cine camera showing my new design;

Fig. 2 is a side elevational view thereof;

Fig. 3 is a bottom plan view thereof;

Fig. 4 is a side elevational view of the opposite side thereof;

Fig. 5 is a front elevational view thereof; and

Fig. 6 is a rear elevational view thereof.

The essential features of the design reside in the portion shown in full lines on the drawing.

I claim:

The ornamental design for a cine camera, as shown and described.
